UNITED STATES PATENT OFFICE.

WILLIAM S. RICHARDSON, OF BOSTON, MASSACHUSETTS.

DESIGN FOR A SOCKET MEMBER OF DETACHABLE FASTENERS.

SPECIFICATION forming part of Design No. 27,865, dated November 16, 1897.

Application filed April 29, 1897. Serial No. 634,485. Term of patent 14 years.

To all whom it may concern:

Be it known that I, WILLIAM S. RICHARDSON, of Boston, in the county of Suffolk and State of Massachusetts, have invented and produced a new and original Design for the Socket Members of Detachable Fasteners, of which the following is a specification, reference being had to the accompanying drawings, forming a part thereof.

10 In the drawings a perspective view of the socket member is represented in Figure 1. Fig. 2 represents in perspective the socket member reversed, and Fig. 3 is a section through it.

15 The invention consists in a design for a socket member of a detachable fastening having a flange a , which may have perforations

a' , and within which flange is a hollow circular rib having outer and inner inclined walls $a^2 a^3$. In other words, the walls $a^2 a^3$ are both 20 inclined at an angle of about forty-five degrees to the plane of the flange a , thus forming a rib which is conical in cross-section, as more clearly shown in Fig. 3.

Having described my invention, what I 25 claim as new, and desire to secure by Letters Patent of the United States, is—

The design for a socket member of a detachable fastener herein shown and described.

WILLIAM S. RICHARDSON.
